UNITED STATES PATENT OFFICE.

DONALD M. BLISS, OF WEST ORANGE, NEW JERSEY, ASSIGNOR, BY MESNE ASSIGNMENTS, TO THOMAS A. EDISON, INCORPORATED, OF WEST ORANGE, NEW JERSEY, A CORPORATION OF NEW JERSEY.

SPARK-COIL.

1,174,225.

Specification of Letters Patent.

Patented Mar. 7, 1916.

Application filed December 7, 1910. Serial No. 596,057.

To all whom it may concern:

Be it known that I, DONALD M. BLISS, a subject of the King of Great Britain, residing at 171 Valley road, West Orange, in 5 the county of Essex, in the State of New Jersey, have invented certain new and useful Improvements in Spark-Coils, of which the following is a description.

My invention relates to spark coils such 10 as are used in sparking gas engines, particularly of the make and break type, but it is also adapted to be applied to other uses, for example, to small transformers for bell ringing circuits and other low voltage 15 work.

More particularly my invention relates 20 to a construction comprising iron stampings or laminæ of a novel type for the magnetic field of a coil and to a casing designed to hold these stampings in place without the use of rivets, screws or a mass 25 of insulating material.

My invention comprises a casing having 30 a body portion provided with integral means for supporting the stampings against downward movement and for maintaining them in contact or properly spaced, and a cover for said body portion engaging the stampings and holding them firmly in place within the casing.

In the form of my invention disclosed, I provide the body portion of the casing with integral projections in the form of ribs having enlargements on which the stampings 35 rest, the ribs coacting with the stampings to hold them in proper relation to each other. I also provide additional projections having horizontal seats to assist in supporting the stampings.

40 My object is to reduce the cost of construction and simplify the design in devices of this character and to provide an easily made and readily assembled device of relatively high efficiency.

45 In order that my invention may be more fully understood, attention is hereby directed to the accompanying drawings forming part of this specification, and in which:

Figure 1 is a central longitudinal vertical section of my improved spark coil taken 50 on the line 1—1 of Fig. 3; Fig. 2 is a cross section thereof taken on the line 2—2 of Fig. 3; Fig. 3 is a horizontal section thereof taken on the line 3—3 of Fig. 1; and Fig. 4 is a detail in section on the line 4—4 of 55 Fig. 3.

In all the views like parts are designated by the same reference numerals.

Referring to the drawings, 1 and 2 are two sets of E-shaped iron stampings, each 60 set comprising a number of laminated members loosely assembled on top of each other to the proper thickness to firmly support on their central cores 3 and 4 respectively, a coil 5 of insulated wire. As shown in Fig. 65 3, coil 5 passes into the slots between the parallel arms and the central cores of the stampings, which latter are made of a size to adapt the coil to the particular use to which it is to be put. When it is to be used 70 as a spark coil for gas engines, I prefer to open the magnetic circuit slightly by making the arms and the cores of the stampings of such a length that when the stampings are assembled in place within the casing 6 75 there is an air gap 7 of predetermined length between parts 1 and 2, so that the coil will operate more rapidly than if the magnetic circuit were completely closed. When using the device as a small trans- 80 former or on alternating current circuits, the arms and cores of the stampings are made of such a length that the two sets of stampings will be in magnetic contact with each other.

85 The casing for the coil and the stampings comprises a rectangular cast metal body portion 8 and cover 9 therefor. The body portion is provided centrally at each side with a projection in the form of a vertical rib 10 having an enlargement 11 on its lower portion and with projections 12, each located in one of the corners of the body portion. The enlargements 11 and projections 12 are each provided with a horizontal seat, all of 90 95 the horizontal seats being preferably in the

same plane and serving to support the stampings firmly. The lower surfaces of the enlargements 12 are flush with the bottom of the body portion. Recesses 13 and 13' are formed in the edges of the stampings centrally of the portions connecting the arms and cores and at the ends of the arms respectively, the recesses being adapted to engage the vertical ribs 10 to hold the stampings in their proper relative positions on the horizontal seats of the enlargements and corner projections.

The cover 9 is made of resilient material and as shown at 14 and 15 Fig. 1, comes 15 presses the edges of the stampings; so that, when it is fastened in place on the body portion 8 by the screws 16, it holds the stampings and the coil carried thereby firmly in position. Binding posts 17 and 20 18 of a well known type, are secured to the body portion and are adapted to connect the ends of the wire of the coil with a circuit containing a source of current supply. In order that the device may be secured 25 upon the desired support, the body portion is provided with perforated ears 19 and 20.

In assembling my improved apparatus, it is simply necessary to superpose the stampings on each other to the proper thickness, 30 to place the coil of wire on the central cores of the stampings, to slide the coil and the stampings into position in the body portion, to fasten the ends of the wire of the coil to the binding posts, and to secure the cover in 35 place. This being done, the stampings are held rigidly in place by the projections described above and by the cover for the casing.

It is evident that numerous changes may 40 be made in the construction described above without departing from the spirit of my invention. Instead of using a cast metal casing, I may use a sheet metal casing with the projections pressed therein so as to lighten 45 the weight and further reduce the cost of the construction. I may also fill the entire space within the casing with some insulating water-proof compound so as to adapt the coil for use in damp places. The insulating 50 compound in this case does not serve to hold the stampings in place, but simply acts as a medium of insulation.

Having now described my invention, what I claim and desire to secure by Letters Patent of the United States is:

1. In electrical apparatus, the combination of a casing comprising a body portion having inwardly extended projections forming vertical ribs and having horizontal seats, 60 and a cover secured to the body portion, and a plurality of superimposed laminae having recesses registering substantially vertically, said laminae being clamped in piles upon said seats by the cover and said ribs engag-

ing recessed portions of said laminae to position said laminae, substantially as described.

2. In electrical apparatus, the combination of a casing comprising a body portion having inwardly extended projections forming vertical ribs and having horizontal seats, 70 and a resilient cover secured to the body portion, and a plurality of superimposed laminae having recesses registering substantially vertically, said laminae being clamped in piles upon said seats by the cover and said 75 ribs engaging recessed portions of said laminae to position said laminae, substantially as described.

3. In electrical apparatus, the combination of a casing comprising a rectangular body portion having at each corner an inwardly extended projection provided with a horizontal seat and having intermediate of said corners inwardly extended projections forming vertical ribs and having horizontal 80 seats, all of said seats being in the same plane, and a cover secured to the body portion, and a plurality of superimposed laminae having recesses registering substantially vertically, said laminae being clamped in 85 piles upon said seats by the cover, and said ribs engaging recessed portions of said laminae to position said laminae, substantially as described.

4. In electrical apparatus, the combination with a coil of wire, of two sets of vertically grooved superimposed laminae, each set having a portion extended into said coil, and a casing having a plurality of projections thereon, said projections including 90 projections having horizontal seats to support said laminae and projections forming vertically extending ribs engaging grooved portions of said laminae to retain the same in proper relation to each other, substantially as described.

5. In electrical apparatus, the combination with a coil of wire, of two sets of vertically grooved superimposed laminae, each set having a portion extended into said coil, 95 said extended portions being separated by an air gap across the magnetic circuit of said coil, and a casing having a plurality of projections thereon, said projections including projections provided with horizontal seats to support said laminae and projections forming vertically extending ribs engaging grooved portions of said laminae to retain the same in proper relation to each other, substantially as described.

6. In electrical apparatus, the combination with a coil of wire, of two sets of vertically grooved superimposed E-shaped laminae, the legs of one set being extended toward but spaced by an air gap from the legs 125 of the other set, the central leg of each set being extended into said coil, and a casing including a body portion having a plurality

of projections thereon, said projections including projections provided with horizontal seats to support said laminæ and projections forming vertically extending ribs engaging grooved portions of said laminæ to retain the two sets of laminæ in properly spaced relation, substantially as described.

This specification signed and witnesses this 6th day of December 1910.

DONALD M. BLISS.
